(57) **CLAIM**

The ornamental design for a product applicator, as shown and described.

DESCRIPTION

FIG. 1 is a front view of a product applicator shown in an open position;

FIG. 2 is a rear view of the product applicator of FIG. 1 shown in an open position;

FIG. 3 is a left-side view of the product applicator of FIG. 1 shown in an open position;

FIG. 4 is a right-side view of the product applicator of FIG. 1 shown in an open position;

FIG. 5 is top view of a handle portion of the product applicator of FIG. 1;

FIG. 6 is a bottom view of the handle portion of FIG. 5;

FIG. 7 is a perspective view of the handle portion of FIG. 5;

FIG. 8 is a top view of a cap portion of the product applicator of FIG. 1;

FIG. 9 is a bottom view of the cap portion of FIG. 8;

FIG. 10 is a front perspective view of the product applicator of FIG. 1 shown in an open position with a product tube coupled to the handle portion, wherein the product tube is shown in broken lines and forms no part of the claimed design;

FIG. 11 is a front view of the product applicator of FIG. 1 shown in a closed position;

FIG. 12 is a rear view of the product applicator of FIG. 1 shown in a closed position;

FIG. 13 is a top view of the product applicator of FIG. 1 shown in a closed position;

FIG. 14 is a bottom view of the product applicator of FIG. 1 shown in a closed position;

FIG. 15 is a left-side view of the product applicator of FIG. 1 shown in a closed position;

FIG. 16 is a right-side view of the product applicator of FIG. 1 shown in a closed position; and,

FIG. 17 is a perspective view of the product applicator of FIG. 1 shown in a closed position.

(Continued)

The dash-dash broken lines depict portions of the product applicator that form no part of the claimed design. The broken lines depicted in FIG. 10 are for the purpose of illustrating environmental subject matter and form no part of the claimed design.
